TRIPPING MECHANISM FOR PRINTING-MACHINES.

1,393,037.

Specification of Letters Patent.

Patented Oct. 11, 1921.

Original application filed May 29, 1919, Serial No. 300,702. Divided and this application filed February 21, 1920. Serial No. 360,332.

To all whom it may concern:

Be it known that I, LEWIS E. MORRISON, citizen of the United States, and a resident of Newark, in the county of Essex and 5 State of New Jersey, have invented certain new and useful Improvements in Tripping Mechanisms for Printing-Machines, of which the following is a specification.

This invention relates to improvements in 10 tripping mechanism for printing machines of the type shown in my pending application, Serial Number 300,702, filed May 29th, 1919, from which application this one is divided out.

15 The object of the invention is to provide a generally improved tripping mechanism particularly well adapted for use in connection with an automatic printing machine such as shown in the said application. The 20 invention, however, is not restricted in its use or application to any particular make of printing press, but is intended broadly for use on platen presses of the Chandler and Price type, well known in the art.

25 Another object of the invention is to provide a tripping mechanism adapted to operate automatically in connection with automatic paper separating and feeding means and automatic gripping or delivery means 30 and designed to operate to trip or stop the press when both or either of said means fail to act. In addition, the tripping mechanism is designed so as to permit of manual operation of the usual tripping means found 35 on presses of the type mentioned.

With these and other objects in view the invention comprises a tripping mechanism as hereinafter described and as illustrated in the accompanying drawings in which—

40 Figure 1 is a general side view of a platen printing press embodying the invention with details omitted.

Fig. 2 is a front view of the press looking in direction of arrow 2 in Fig. 1.

45 Fig. 3 is a detail view of parts of the tripping mechanism.

Fig. 4 is a view of the tripping mechanism looking in the direction of the arrow 4 in Fig. 3.

50 Fig. 5 is a sectional view of parts shown in Figs. 3 and 4.

Fig. 6 is a detail view of the lower end of the tripping link.

Fig. 7 is a view on line 7—7 of Fig. 6.

Fig. 8 is a diagrammatic view of the tripping mechanism and associated parts.

Fig. 9 is a detail view of parts of the electrical connections.

Fig. 10 is a detail view looking in the direction of arrow 10 in Fig. 8.

The press as illustrated in outline only in Figs. 1 and 2 is a typical platen or job press. The frame of the press is denoted in general by the reference numeral 3. 4 is the driving shaft; 5 the platen pivot; 6 the platen; 7 the form member pivoted at 8; 9 indicates the inking mechanism; 10, 10 the connecting rods and 12 the platen locking cam which appears as and also acts as a crank disk as shown. 13 is the tripping means usually found on presses of this type and 14 is the normally operated tripping lever. All of the aforesaid parts and their function are well known in the art.

On the left side of the press and suitably secured to the frame thereof is a bracket 15 having a rearwardly inclined upright 16 and a depending forward portion or bracket 17. On the right side of the press there is a similar bracket 18, Fig. 2, having an upright 16 and a bracket 17.

In addition the bracket 18 has a forwardly inclined upright 19. The numeral 24 denotes a paper feed table which is pivotally supported on the bracket 19 by means not disclosed herein. The feed table rests normally on the said two uprights 16, 16 on shoulders 26 thereon. The paper 52 is supported on the feed table 24 by means of a paper board 40.

The top sheet is separated from the pile of paper 52 by a suction nozzle 53 secured to a rod 54 supported in an arm 56. To the connecting rods 10 there is secured a bracket 57 which is U shaped and passes across the press in the rear thereof. One arm of the U, on the right side of the press, is extended upward and forms a support 59, to which the said nozzle arm 56 is pivoted at 60. It follows that as the form member moves back and forth, the nozzle arm with the nozzle is moved likewise and the paper, after having been picked up by the nozzle, is transferred from the pile and to the platen as will be understood. 61, 61 are coöperating stops on the arm 56 and support 59 respectively whereby the arm may be swung upward into the dotted position shown in Fig.

1, and thus the nozzle moved out of the way whenever desired. Suitable guiding means for the nozzle arm is provided, but are not shown herein.

- 5 The printed or unprinted paper is removed from the platen by the gripper 130 which comprises a fixed lower jaw 131 and a pivoted upper jaw 132. The upper jaw is operated to open and close by a toggle joint 133 actuated by a gripper operating means as 135. The gripper is secured to a gripper carriage 112 which slides on rods 110 under the feed table 24. Secured to the gripper carriage is a sliding bearing 119 10 which slides on a rod 120. 124 is a gripper carriage operating link which is pivoted to said sliding bearing 119 and to the inking mechanism 9 at 125 upon the frame thereof; see Fig. 1.
- 15 It will therefore be understood that as the press opens, the gripper is moved toward the platen to seize the sheet and remove it therefrom. And as the press closes, the gripper moves forwardly under the feed table and 20 is opened at the proper time to drop the sheet in a suitable delivery receptacle, not shown.
- 20 Means are provided for tripping the form or tripping the press as it is usually stated.
- 25 30 In this instance, means are provided for operating the usual tripping lever 14 to actuate the usual tripping mechanism on the press in case the suction nozzle fails to pick up a sheet and feed it to the platen, and in 35 case the gripper fails to remove the printed sheet from the platen. See Figs. 1, 2, and 3 to 10 inclusive.

Referring to Fig. 1, the form 190 is as usual connected to an eccentric shaft 191 40 by means not shown. 192 is an arm secured to the shaft and which arm is connected by a link 193 to another arm 194 fast to a shaft 195. The latter is provided with a slotted arm 196. 197 is a pin which plays in the slot in the arm 196 and which pin is fast in a locking arm 198 mounted on a second shaft 199. Outside the frame the shaft 199 carries an arm 200 connected by a link 201 to the tripping lever 14 which 45 is pivoted at 202. All of the foregoing is well known in the art.

When the tripping lever 14 is thrown by the operator—to the left in Fig. 1—the shaft 199 is rotated anti-clockwise. The shaft 195 50 is rotated clockwise. The link 193 is lifted and swings the arm 192 upward, thereby rotating the eccentric shaft 191 to withdraw or trip the form 190, all in a well known manner.

- 55 60 The present automatic tripping and untripping mechanism comprises the following elements. See Figs. 3 to 10 inclusive. To the bottom of the tripping lever 14 is pivoted a head 210 by means of a stud 211.
- 65 The head is provided with a slot 212. 213

is a trip cylinder secured to the head 210 by screws 214. Within the cylinder there is a plug 215 having a shoulder 216. 217 is a spring urging the plug outward. The cylinder is connected by a hose 218 to the pump 219, and is provided with a slot 220 adapted to receive the latch 221 which is pivoted on said cylinder at 222. The latch is urged inward in said slot 220 and against the plug 215 by a spring 223. The latch also carries a roller 224 and is operated by the tripping link 225 which is pivoted to the U-shaped bracket or frame 57 at 226, see Fig. 1.

The link 225 is adapted to slide in the slot 212 in the head 210 and is provided with a shoulder 228 adapted to take against the shoulder 216 on the plug 213 and a ledge 229 whereby said link is kept occupying the full depth of the slot 212 as will be understood from Fig. 5. The link carries a fixed unlatching finger 230 and a movable unlatching hook 231 pivoted at 232 and adapted to be operated by a magnet 233. The finger 230 is adapted to contact with the roller 224 to depress it so as to move the latch out of the slot 220. Similarly, the hook 231 is adapted to contact with a post 234 on the latch to lift the latter to the same effect. 235 is a slot in the link 225 and 236 a button or projection.

95 Mounted on the frame of the press is an air release 240, Fig. 8, comprising a fixed bracket 241 having an air hole 242 connected to the pump by hose connection 243. Pivoted on said bracket 244 is an arm 245 having a hole 246 through which a link 247 is adapted to slide. The link has a notch 248 and the arm 245 has a lever 249. The latter has a pin 250 which passes through a hole in the arm 245 and into the hole 246 through which the pin is adapted to enter the notch 248 in the link 247. The lever 249 is pivoted at 251 and a spring seated pin 252 acting against the short arm 253 of the lever 249 normally keeps the pin 250 down in engagement with the notch 248 in the link 247. 254 is an eye in the lever 249 connected by a chain 255 to a switch lever 256. The pump 219 is pivoted to the floor at 257 and the piston rod 258 from the pump piston is 100 connected at 260 to the gear 261 on the press. 110

Referring now to Fig. 2, it will be seen that if the suction takes place through the hose 300, the nozzle 53 picks up a sheet. Suction then also occurs in the trip cylinder 213, whereby the plug 215 is sucked or moved inwardly and the latch 221 under influence by the spring 223 snaps in front of the plug and rests against the shoulder 216 thus keeping the plug away from the trip 120 operating link 225 which as the press opens slides idly in the slot 212 in the head 210. The sheet is then deposited on the platen as air is permitted to enter below the pump piston as will be presently explained.

Next the press closes for printing and the link 225 moves through the head 210. Immediately after the shoulder 228 on the link has passed the plug 215, the fixed finger on the link hits the latch roller 224 and unlatches the plug, which thereupon is moved out by the spring 217 and now rests against the surface of the link 225. After printing the press again opens and 10 if suction occurs, the above mentioned operation is repeated and the link 225 has at no time been in operative connection with the tripping lever 14.

That is to say, normally the plug 215 projects into the path of the shoulder 228 on the link 225 and if it remained in that position the shoulder 228 would catch said plug and move the tripping lever and trip the press. But because the suction operates 20 properly, the plug is sucked out of the path of the shoulder 228 and latched. But as soon as the said shoulder has passed the plug, the latch is operated by the link finger 230 to unlatch the plug which then moves outward ready for the next operation. And inasmuch as the tripping mechanism has not operated, the air release 240 remains undisturbed.

If, however, the suction fails to act so 30 that air enters through the nozzle 53, the plug 215 will remain in its projected or outward position as shown in Fig. 5. Consequently, when the press is closed for printing, the shoulder 228 on the link 225 will 35 catch said plug, that is, the link will become operatively connected with the tripping lever and throw the latter, thereby tripping the press, and at the same time, the operation of the tripping mechanism will cause the 40 shaft 199 therein to be rotated anti-clockwise as explained and through an arm 292 fast on said shaft, the link 247 connected to the air release will be operated and the arm 245 thereof will be moved forward on the 45 pivot 244 and the air hole 242 will be uncovered and air will pass into the pump. Continuing the operation of the press, on the opening stroke, the button 236 on the link 225 will abut the head 210 fast to the 50 tripping lever and carry the latter back to a position, thereby untripping the press. On the next stroke, the press will again be tripped, because air having entered through the air release, suction will again fail, so 55 that after one tripping because of failure of the suction, the press will continue tripping until the cause of the trouble is located and attended to and the air release set to cover the air opening 242.

60 The air release is set or rendered inactive as follows. When the operator discovers that the press is tripping, he lifts the switch handle—or whatever other element the chain 255 is attached to—thereby lifting the lever 65 249 and lifting the pin 250 out of engage-

ment with the socket in the link 247. The latter will therefore no longer operate the arm 245 to uncover the air hole. The arm 245 is moved into normal position by the collar 291 on the link 247, Fig. 10. 70

The tripping mechanism is also arranged to trip automatically in the event that the gripper fails to take a sheet from the platen, as for instance when the sheet is torn and cannot be reached by the gripper or for 75 other reasons. In this case the unlatching of the latch 221 so as to permit the plug 215 to move into the path of the shoulder 228 on the link 225 is done electrically in advance of the movement of said shoulder.

Accordingly, an electric circuit is established on the press comprising the following elements. A thin strip of brass 265 is attached to the movable jaw of the gripper, but insulated therefrom as seen in Fig. 8. 80 A wire 266, passes from said gripper contact 265 to a contact 267 on the gripper carriage Fig. 9. During the operation the contact 267 slides against a brass spring contact 268 carried by the feed table and which makes contact with a spring seated button 269 carried by the frame. From the button a wire 270 leads to the battery 271. Fig. 9, merely illustrates the manner in which the circuit is established between the 90 feed table and the frame.

In Fig. 8, the contacts 267 and 268 are shown diagrammatically and the circuit is as follows. From the battery 271, wire 270, contacts 268 and 267, wire 266 to the gripper contact 265. From the other side of the battery, to the switch 256 to the magnet 233 and to ground on the frame. 100

When the gripper moves in over the platen to take a sheet, contact is established 105 between contacts 267 and 268. If there is no sheet on the platen for the gripper to take, closing of the gripper establishes the circuit as follows.

From battery to gripper contact 265, 110 through the frame to the magnet 233 to the switch and back to the battery. Consequently the magnet is energized and when the press closes for printing the hook 231 will be in the path of the post 234 on the latch, lift and keep the latter away (due to the round shape of hook 231) from the plug 215 which will be caught by the shoulder 228 and the press tripped. This in turn 115 operates the air release and prevents further feeding of the paper to the platen. Thereafter the switch is opened to reset the air release and break the circuit. The trouble is thereafter attended to. The press then 120 commences to operate again and the switch is left open until after one sheet has been fed to the platen, after which the switch is closed. If the switch is closed sooner, the press will again be tripped because there is 125 then no sheet for the grippers to act upon. 130

While operating by hand there is of course no suction and consequently the plug 215 in the trip cylinder would remain in the path of the shoulder 228 on the link 225 and the 5 press tripped constantly unless some provision is made to the contrary. Accordingly, there is pivoted at 275 on the tripping lever 14 a link 276 having a hand grip 277. The link 276 is at its bottom, see Figs. 4 and 5, 10 pivoted to a bell crank 278 pivoted at 279. The bell crank 278 has a nose 280 adapted to engage a pin 281 which in turn is designed to contact with the plug 215. When operating the press for hand feeding, the hand 15 grip 277 is tied down as it were to the gripping lever by a ring or loop 283 to lift the link 276. This in turn operates the bell crank 278 and the nose 280 thereof moves the pin 281 inwardly and pushes the plug 20 215 back into the cylinder 213. Thus, during hand operation, the plug is kept permanently out of the way of the tripping shoulder 228 and as the link 225 moves with the form member of the press, it slides idly 25 past the tripping lever without tripping. If the operator desires to trip the press he throws the tripping lever as usual. In Fig. 5 parts of the bell crank 278 are shown dotted for the sake of clearness.

30 It will be seen, therefore, that in the event the suction means for picking up the paper or the gripping means do not function properly, the press will be automatically tripped, and that these mechanisms do not 35 interfere with the manual operation of the trip. It will further be understood that changes may be made in the detailed construction and arrangement of the mechanisms herein disclosed without departing 40 from the principle of the invention or the scope of the appended claims.

I claim:—

1. The combination of a tripping mechanism, a tripping lever for actuating it, a link for operating said tripping lever, a member mounted on said tripping lever and normally in the path of said link, suction means for moving said member out of the path of said link, a latch for locking said 50 member in its removed position and means on said link for unlatching the said member.
2. The combination of a tripping mechanism, a tripping lever for actuating it, a link 55 for operating said tripping lever, a member mounted on said tripping lever, means for normally maintaining said member in active position in the path of said link, suction means for moving said member out of the path of said link, a latch on said tripping lever for locking said member in its removed position and means on said link for unlatching said member.
3. The combination of a tripping mechanism, a tripping lever therefor, a movable 65

link for actuating said tripping lever, a member on said tripping lever, a spring for normally maintaining said member in active position in the path of said link, suction means for moving said member into 70 inactive position, a latch pivoted on said tripping lever, a spring for operating said latch to lock said member in inactive position and means on said link for unlatching the said member. 75

4. The combination of a tripping mechanism, an operating lever therefor, a member mounted on said lever, a spring for holding said member in normal active position, a link having a shoulder adapted to engage 80 said member in its active position to operate said lever, suction means for moving said member into inactive position, means for maintaining said member in inactive position while the said link moves past the same 85 and means on said link for restoring the said member.

5. The combination of a tripping mechanism, an actuating lever therefor, a link, a movable member for operatively connecting said link and the said lever to operate the latter, suction means for moving said connecting member into inactive position, a latch for locking said member in active position and electrically operated means for 90 unlatching the said connecting member. 95

6. The combination of a tripping mechanism, an actuating lever therefor, a link, a movable member for operatively connecting said link and the said lever to operate the 100 latter, suction means for moving said connecting member into inactive position, a latch on said tripping lever for locking said member in inactive position and electrically operated means on the said link for unlatching 105 the said connecting member.

7. The combination of a tripping mechanism, an actuating lever therefor, a movable member, means for operatively connecting the latter and the said lever, suction means for rendering said connecting means inactive, and a spring for maintaining said connecting means in active position if said suction means fails to operate. 110

8. In a printing press the combination 115 of a tripping mechanism, a suction operated sheet separating mechanism, a pump for applying suction thereto, means including an electric circuit and a switch for causing the said tripping mechanism to act when the said suction mechanism fails to operate, an air release for supplying air to the pump under the piston thereof when the said tripping mechanism has been actuated, and connecting means between said air release and 120 the said switch for automatically rendering said release inoperative when the said circuit is broken by operation of the said switch. 125

LEWIS E. MORRISON.
